UNITED STATES PATENT OFFICE.

ALBERT J. LOEPSINGER, OF PROVIDENCE, RHODE ISLAND, ASSIGNOR TO GENERAL FIRE EXTINGUISHER COMPANY, OF PROVIDENCE, RHODE ISLAND, A CORPORATION OF NEW YORK.

DRY-PIPE SYSTEM.

Application filed April 18, 1922. Serial No. 554,911.

To all whom it may concern:

Be it known that I, ALBERT J. LOEPSINGER, a citizen of the United States, residing at Providence, in the county of Providence and 5 State of Rhode Island, have invented certain new and useful Improvements in Dry-Pipe Systems, of which the following is a specification.

This invention relates to dry pipe distribution systems. More particularly it is designed, and its use is here illustrated, for systems in which there is a source of supply of water or other fire extinguishing fluid and a distribution system of piping from 10 which either open or automatic sprinklers, or other discharge means, is provided; this piping being normally filled with air, and the whole arranged for the extinguishing liquid, which is held in readiness, to pass 15 through whenever the need arises. Ordinarily the supply is held back by a so-called dry pipe valve which opens automatically when the occasion demands, either because of the reduction of pressure in the system 20 which follows upon the opening of a sprinkler head or because of the transmission of an impulse of some other nature from the region where the fire occurs. But in some cases and especially where the liquid 25 used is of a corrosive nature, there is danger of the dry pipe valve failing to operate owing to corrosion having occurred; and in these cases it is considered necessary either to dispense with the automatic feature and 30 to rely upon the presence and action of a human operator to open the valve, being summoned by an alarm when the fire breaks out, or to make the interior metal surfaces of the valve inert by some method, as by 35 coating with lead. Both of these methods are objectionable, the first as being uncertain and slower than automatic systems, and the second as being inconvenient and expensive, particularly when the coating has to be applied to valve bodies and other necessarily 40 odd shaped surfaces.

It is an object of the present invention to provide automatic means for admitting the extinguishing fluid into the distributing system upon the occurrence of a fire, which means dispenses with the need for a dry pipe valve of any type ordinarily signified by that term. It is an advantage of the invention that its principle is applicable either

to open-sprinkler or automatic-sprinkler systems, and accordingly it is a further object of the invention to provide apparatus which makes possible the application of the principle to all sprinkler systems in general, and to the systems of these two types in particular.

The objects of the invention are accomplished by providing a system of distribution piping which normally contains air, either at or above atmospheric pressure 65 without any valve intervening between it and the source of supply and in position to be affected by the liquid which is held ready to be supplied. In fact there need be no valve whatever intervening in a distribution system under atmospheric pressure, and only a check valve, both sides of which are exposed to air, in a system normally above such pressure. To this end the supply of fire extinguishing liquid is stored in a tank 70 so located and connected to the distribution system, that the liquid has free passage to the latter and yet is normally held back from it by the force of gravity. For example the tank may be in the basement of a 75 building below the distributing pipes, or may be on the roof with an upward loop of pipe above the level of the fluid leading to the system below. There is provided a supply of stored energy adapted when the need 80 arises, to force the contents of the storage tank into the distribution system. In the embodiments of the inventions shown in the drawings for illustrative purposes, there is provided an air pressure tank and a valve 85 separating it from the liquid tank, which valve is the control valve of the system and is exposed only to air on each side. Suitable apparatus is provided to operate this valve, as by a thermostatic contrivance in the case 90 of an open sprinkler system; or by reduction of air pressure in the distribution system employing closed sprinklers. In either event, upon the opening of the air control valve the extinguishing liquid is forced into 95 the distribution system.

The application of the invention to both open and closed sprinkler systems is herein illustrated, but it will be understood that variations may be made from the precise apparatus illustrated and also that although in each case the pressure supply is shown applied only to a single liquid supply tank

it might be applied to a plurality of tanks, and if desired those tanks might have different liquids in them; and the distribution systems from them might not cooperate, according as may be desired in any particular case, the advantage of cooperation being manifest in the so called chemical system where the mixture of two liquids is effected to produce by chemical reaction a fire extinguisher gas or foam formation.

It is intended that the patent shall cover by suitable expression in the appended claims whatever features of patentable novelty exist in the invention disclosed.

15 In the accompanying drawings:

Figure 1 is a representation, in elevation and somewhat diagrammatic, of the application of the invention in connection with an open sprinkler system;

20 Figure 2 is a similar representation of an application of the invention to a closed sprinkler system;

25 Figure 3 is a diagrammatic representation of an application of the invention to a plural liquid system; and

Figure 4 is a diagrammatic representation of a modified arrangement applicable to the devices of Figures 1, 2, and 3.

Referring to the drawings the fire extinguishing liquid is maintained in a supply tank 1 which as illustrated in Figures 1, 2 and 3 is located below the level of the sprinklers 2, 2'. It being then necessary to force the liquid from the tank into the distribution system 3 one convenient method of so doing is to admit pressure to the top of the storage tank to force the liquid through a discharge pipe 4 connected to the tank near its bottom and leading upward to the distribution system. The pressure may be provided in various ways, one of which is illustrated in the drawings, wherein is shown a pressure tank 5 from which air may be introduced to the storage tank through a pipe connection 6 between the two. In this pipe is located a control valve 7, 7' which is normally closed to hold back the air pressure from the storage tank but which may be opened automatically when the need arises to admit the pressure to the liquid tank and force the fire extinguishing agent through the system.

In Figure 1 the invention is illustrated as it may be applied in connection with open sprinklers 2, in which case the control valve 7 is preferably one that is electrically operated upon the fusing of any one of a series of thermostatic responsive elements 8 distributed in the areas to be protected by the system. The fusing of one of these elements closes an electric circuit through the operating means 9 of the control valve 7, whereupon the latter is caused to open. This admits air pressure from the air supply tank into the storage tank which in turn forces

out the liquid into the distribution system from which it is discharged through the sprinklers. While the system is ready and waiting to operate, the liquid storage tank is vented to the atmosphere through an automatic ball drip valve 10 conveniently located in the air pipe 6 on the tank side of the control valve. This vent prevents the building up of any pressure in the storage tank which might be caused by evolution of gas from the fire extinguishing liquid, by expansion or otherwise. Upon the control valve opening, the drip valve is automatically closed by the sudden rush of air so that none of the latter is lost during its action upon the liquid.

When closed sprinklers 2' are employed, another method of controlling the air pressure may be adopted, such as is illustrated in Figure 2. In this arrangement the distribution system 3 is supplied with air pressure through a by-pass pipe 11 leading from the air supply tank 5. In the distribution pipe, between the entrance point 11' of the by-pass and the connection 4' with the discharge pipe of the liquid storage tank, there is provided a check valve 12 having a single clapper 12' so pivoted as to be closed on its seat by the air pressure in the distribution system. The function of this check valve is to prevent this air pressure from acting on the liquid in the storage tank, so that the pressure on the liquid during static condition of the system, may be substantially atmospheric, this being insured by the presence of automatic ball drips 10 suitably connected to both the discharge pipe 4 and the storage tank 1 above the level of the liquid therein.

The by-pass pipe 11 is also connected to a chamber at one end, in this case the top, of a control valve casing 7', whose body constitutes part of the passage 6 between the air and liquid tanks, comprising a pipe from the air tank 5 entering the bottom of the casing and a pipe to the liquid tank 1 passing out from the side of the casing. Within this casing is housed the control valve, comprising a valve stem 13 having at its lower extremity a relatively small disk or poppet valve 14 adapted when seated to close off the pressure supply tank 5 and thus cut off the air supply to the liquid tank. On the upper end of the stem is a larger piston or diaphragm 15 whose perimeter fits the wall of the casing, and upon which the air pressure in the by-pass pipe 11 is exerted. The air pressure therefore acts upon both ends of the valve stem and since the intensity of pressure on both is the same, assuming the system to be quiet and ready, the poppet valve is held to its seat by the greater total of effective pressure downward on the diaphragm. If the total or effective downward pressure on the diaphragm 15 falls to less than that upward on the poppet valve 14, the latter will rise and let air pass through 6

from the supply tank to the top of the liquid tank 1. This occurs upon the opening of a sprinkler head, for such opening at once vents the distribution system to the atmosphere allowing the pressure in it and the by-pass pipe 11 to fall. This reduction of pressure is made possible by the action of a small restriction valve 18 placed in the by-pass close by the supply tank, whose opening 5 is much smaller than that of any sprinkler. Accordingly, upon the opening of one of the latter air flows out of the distribution system and by-pass 11 faster than it enters through the restriction 10 15 18, thereby rapidly reducing the effective pressure on the diaphragm and presently allowing the control valve 14 to rise and open the air passage between the tanks. When the poppet valve 14, has been thus 20 lifted from its seat, its return thereto is prevented during discharge by the engagement of a lug 13' on its stem with a latch 16 arranged in the valve casing. This latch is held back against its impelling spring by 25 the lug so long as the poppet is in its low seated position, but snaps into retaining position under the lug as soon as the latter moves upward a short distance. This locking of the poppet valve open prevents its 30 closure should the pressure on the diaphragm increase due to the backing up of the liquid through the by-pass pipe, or should the pressure in tank 5 diminish greatly. A safety valve 17 prevents over 35 charging when air pressure is being stored in the system.

Figure 3 is a diagrammatic representation of the arrangement of the connection when the invention is applied to a double storage 40 tank system. In this embodiment the control valve 7" admits air to both liquid tanks 1, 1' so that upon the opening of the poppet 14, the air enters both simultaneously. The discharge therefrom will be as may have 45 been arranged, either into a single distributing pipe, if desired, or, and as illustrated, assuming the liquids to be of different kinds, into separate conduits 3, 3' to sprinklers 2" designed for plural liquid discharge as in a 50 chemical or foam system. Although the control valve of Figure 3 is shown as the type of valve used in the apparatus of Figure 2, it is obvious that other types of valves could equally well be employed. If 55 the former is employed, and the distribution is through separate pipings, the by-pass pipe 11 would be connected to a short pipe 11' joining the two lines of distribution beyond the check valves 12 and 12', so that the air 60 pressure in both systems would be equal. Although shown of unequal length in the drawings, the distance traveled by each liquid in moving from the separate tanks to the sprinklers can be made in practice substantially equal, so that both liquids will ar-

rive at the sprinkler at the same time and thereby produce the proper mixture for suitable chemical reaction.

Figure 4 illustrates an arrangement by which a smaller supply of stored air and smaller pressure will serve, the liquid storage being on the roof of the building and its escape into the distribution system prevented only by an upward loop of the discharge pipe 4. Once started the liquid will flow with greater force by gravity, and by siphon action.

I claim as my invention:

1. A dry pipe system comprising a distributing pipe, means open to atmosphere for holding a supply of liquid therefor, whose location and connections afford free passage for the liquid into the distribution pipe, and yet normally hold it back therefrom, as by gravity; means having a supply of compressed air adapted when released to flow into said holder; means actuated by inrush of air for closing said holder to atmosphere whereby said air forces said liquid into said pipe; and temperature controlled means for releasing said air. 85 90

2. A dry pipe distribution system including, in combination, a distributing pipe containing fluid under pressure greater than atmosphere, means for holding a supply of liquid therefor at atmospheric pressure, comprising a connection from said holding means to the distributing pipe at a level above the level of said liquid; means in said connection for holding back the pressure in the distributing pipe, adapted to permit flow of liquid thereto; and means held in restraint and adapted when released to exert pressure upon said liquid to raise it through 100 105 said connection to the distributing pipe. 95

3. A dry pipe distribution system including, in combination, a distributing pipe containing fluid under pressure greater than atmosphere, means for holding a supply of liquid therefor at atmospheric pressure, comprising a connection from said holding means to the distributing pipe at a level above the level of said liquid; means in said connection for holding back the pressure in the distributing pipe, adapted to permit flow of liquid thereto; means held in restraint and adapted when released to exert pressure upon said liquid to raise it through 110 115 said connection to the distributing pipe; and means actuated by rise of temperature to release said restrained means. 120

4. A dry pipe system, comprising a distributing pipe; means holding a supply of liquid therefor, whose location and connections afford free passage for the liquid into the distributing pipe and yet normally hold it back therefrom, as by gravity; means holding a supply of air under pressure, connected with the distributing pipe through 125 130

1. a passage having a restriction permitting only slow flow of air therethrough; a check valve preventing flow of air in the distributing pipe to the liquid; and means connecting said air supply with said liquid supply, comprising a valve having differential surfaces exposed to the air pressure in the air supply and to the air pressure in the distributing pipe; said valve being normally closed, and being opened when the pressure in the distributing pipe falls, whereby the air supply is permitted to flow to said liquid to force it into the distributing pipe.

5. A dry pipe system comprising a distribution system under air pressure having closed automatic sprinklers; air pressure supply means connected thereto through a passage having a restriction permitting flow of air only at a rate slower than it can flow 15 out from the system through the open sprinkler; a supply of fire extinguishing liquid having separate connections to the distribution system and to the air pressure supply means; a check valve in its connection to the distribution system, normally closed by the air pressure in the system, but adapted to open upon surge of the liquid through it; and a control valve in the connection to it from the air supply; 20 said control valve being open to and normally seated by the pressure in the distribution system; said control valve being adapted to open upon the reduction of pressure in the distribution system, and thereby to admit air pressure to the liquid supply and cause discharge of said liquid into the distribution system.

6. A dry pipe system comprising a distribution pipe, a holder for liquid that is 25 to be distributed, and an air pressure supply tank, these elements being arranged with relative location and connections affording

free passage for the liquid into the distributing pipe and yet with the liquid normally held back therefrom, as by gravity, and with the air pressure adapted to be applied to the liquid to force it into said distributing pipe, and yet normally held back therefrom by a control valve; connections from the liquid surfaces to atmosphere, adapted to be closed by rush of fluid; a connection from the air pressure tank to the distribution pipe, whereby air pressure is maintained in the latter, said connection being through a restricted passage permitting only slow flow of air and there being a check valve 55 between the distribution pipe and the liquid supply; and a control valve for the connection between air supply and liquid supply, normally held closed by the pressure in the distribution pipe and adapted to open automatically upon fall of such pressure, thereby permitting the air to force the liquid into the distribution pipe.

7. A dry pipe system comprising a distributing pipe containing fluid under pressure greater than atmosphere, liquid supply therefor having a vent normally open to atmosphere and closable upon increase of pressure on said liquid supply, air pressure means for forcing the liquid into the distributing pipe, and a dry pipe valve oppositely pressed by air in the distribution system and by air in the air pressure supply; and connections whereby said dry pipe valve, opening upon diminution of the distribution system pressure upon it, admits air pressure to said liquid supply to close its vent and to force the liquid into the distribution system.

Signed at Boston, Massachusetts this 80
seventeenth day of April, 1922.

ALBERT J. LOEPSINGER.
